UNITED STATES PATENT OFFICE

123,795

DESIGN FOR A LACE

Edward E. Bancroft, West Warwick, R. I.

Application September 25, 1940, Serial No. 95,354

Term of patent 3½ years

To all whom it may concern:

Be it known that I, Edward E. Bancroft, a citizen of the United States, residing at West Warwick, in the county of Kent and State of Rhode Island, have invented a new, original, and ornamental Design for a Lace, of which the following is a specification, reference being had to the accompanying drawing, forming a part thereof.

The figure is a front elevational view of a piece of lace, showing my new design.

I claim:

The ornamental design for a lace, as shown,
EDWARD E. BANCROFT.
